John A. Salvia, Rochester, N.Y., assignor to Wilmot
Castle Company, Rochester, N.Y., a corporation of
New York

Application August 28, 1958, Serial No. 52,413

Term of patent 14 years

(Cl. D48—20)

FIG.3

Fig. 1 is a perspective view of a supporting standard for a lamp or the like, showing the new design with portions of the patterned detail of the central portion of the base member omitted for convenience of illustration, it being understood that said pattern covers the entire central portion of the base as shown in Fig. 2.

Fig. 2 is a top plan view thereof;

Fig. 3 is a side elevation thereof, with the upper portion broken away for convenience of illustration; and

Fig. 4 is a bottom plan view thereof.

I claim:

The ornamental design for a supporting standard for a lamp or the like, substantially as shown.
